US00D565696S

(12) **United States Design Patent** (10) Patent No.: **US D565,696 S**
Mihlbauer et al. (45) Date of Patent: **** Apr. 1, 2008**

(54) **AQUARIUM FILTER CARTRIDGE ELEMENT**

(75) Inventors: **Brad L. Mihlbauer**, Mukwonago, WI (US); **David R. Troop, II**, Kenosha, WI (US); **Lonnie Austin Ready**, West Columbia, SC (US); **Giacomo Guoli**, Milan (IT); **Fabio Bellia**, Trebaseleghe (IT)

(73) Assignee: **Central Garden and Pet Company**, Walnut Creek, CA (US)

(**) Term: **14 Years**

(21) Appl. No.: **29/278,645**

(22) Filed: **Apr. 5, 2007**

(30) **Foreign Application Priority Data**

Oct. 5, 2006 (IT) PD2006A0367
 Mar. 8, 2007 (EP) 07103798

(51) **LOC (8) Cl.** **23-01**

(52) **U.S. Cl.** **D23/210**

(58) **Field of Classification Search** D23/209, D23/210; 210/167.27, 167.25, 484, 485

(57) **CLAIM**

The ornamental design for an aquarium filter cartridge element, as shown and described.

DESCRIPTION

FIG. 1 is an isometric view of an aquarium filter cartridge element incorporating our new design;

FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a rear elevation view thereof.

The broken lines are for illustration only, and form no part of the claimed design.
